(57) **CLAIM**

We claim the ornamental design for a steering wheel, as shown and described.

DESCRIPTION

FIG. 1 is a right-side and front perspective view of a steering wheel of the claimed design;

FIG. 2 is a front elevational view thereof;

FIG. 3 is a rear elevational view thereof;

FIG. 4 is a left side view thereof;

FIG. 5 is a right side view thereof;

FIG. 6 is top view thereof; and,

FIG. 7 is a bottom view thereof.

The broken lines in the drawings are for illustrative purposes only and form no part of the claimed design.
